CLAIM

The ornamental design for an engine enclosure of a self-propelled sprayer, as shown and described.

DESCRIPTION

FIG. 1 is an isometric view of an engine enclosure of a self-propelled sprayer in accordance with the present invention;

FIG. 2 is a rear elevation view of the engine enclosure of FIG. 1;

FIG. 3 is a side elevation view of a first side of the engine enclosure of FIG. 1;

FIG. 4 is a top plan view of the engine enclosure of FIG. 1;

FIG. 5 is a side elevation view of a second side of the engine enclosure of FIG. 1; and,

FIG. 6 is a front elevation view of the engine enclosure of FIG. 1.

The broken line showing of the sprayer vehicle is included for the purpose of illustrating environmental structure only and forms no part of the claimed design.
